UNITED STATES PATENT OFFICE.

HERBERT C. TAYLOR, OF GREENSBURG, INDIANA.

OVEN.

Application filed December 5, 1921. Serial No. 519,945.

To all whom it may concern:

Be it known that I, HERBERT C. TAYLOR, a citizen of the United States, and a resident of Greensburg, county of Decatur, and 5 State of Indiana, have invented a certain new and useful Oven; and I do hereby declare that the following is a full, clear, and exact description thereof, reference being had to the accompanying drawings, in which 10 like numerals refer to like parts.

The object of this invention is to provide an oven with an adjustable partition or partitions so as to adapt the oven for use with a minimum number of burners or one 15 burner, depending upon the size thereof, such as shown and disclosed in my Letters Patent No. 1,109,263 issued September 1, 1914, for an adjustable oven.

Whereas the object of the invention is to 20 decrease the dimensions of the heating compartment, whereby a large size oven may be readily adjusted to a smaller size oven with one or more compartments of the desired capacity, it is the particular feature of 25 this invention to hingedly mount the adjusting partition member within the chamber for accomplishing this purpose.

By means of this arrangement a partition 30 may at all times remain within the oven when not in use or may be readily swung to operative position for dividing the compartment as above set forth. This results in not only a means for reducing fuel consumption and quicker heating of the compartment 35 when reduced in dimensions, but enables the positioning and adjusting of the partition within the oven more readily and easily than is the case with the sliding partition.

The full nature of this invention will be 40 understood from the accompanying drawings and the following description and claims.

In the drawings Fig. 1 is a perspective view of the oven placed upon a stove over a 45 burner. Fig. 2 is a section taken on the line 2-2 of Fig. 1. Fig. 3 is a section taken on the line 3-3 of Fig. 2. Fig. 4 is the same as Fig. 2 showing a modified form. Fig. 5 is a section taken on the line 5-5 of Fig. 4.

50 In the drawings there is shown an oven 10 suitable for a gas, oil or electric stove and receiving heat from the burner or burners of a stove 11. Said oven is formed of sheet metal in the well known manner and with 55 the usual drop door 12 provided with latches 13 for securing it in closed position. The

central portion of the bottom is cut away to allow the heat from the several burners to pass upward into the oven. A heat deflector 14 is spaced mid-way between the front 60 and rear walls and deflects the heat from the burners toward said front and rear walls, said heat deflector having a sheet metal top extending in a horizontal plane, and angularly disposed sides 15 formed on the under 65 side thereof forming a triangle in cross section and thereby causing the heat deflected thereunder to be deflected laterally toward the front and rear of the oven, as shown in Fig. 3. Surrounding the oven, between the 70 outer walls thereof and the inner walls 16, there are formed dead air spaces 17 by the spacing of said walls for insulation purposes so as to reduce the radiation of the heat from the oven, all of which construction is of the 75 usual type well known in the art.

Mounted on the inner wall 18 of the top of the oven there are provided a pair of longitudinal guide rods 19 rigidly secured at each end and spaced from said wall, as 80 shown in Fig. 2. Suspended from said rods and slidably mounted thereon there is an adjustable partition member 20 formed in a similar manner to the permanent walls of the oven and provided with the dead air 85 space 17 above described. Said partition member is, therefore, capable of dividing the oven into two compartments of reduced dimensions and insulating to an appreciable extent the used compartment from the unused compartment. The partition member 90 is provided with hinges or hooks 21 mounted in sliding engagement with the rods 19 so as to hingedly secure said partition member to the top wall of the oven, permitting it to 95 swing into vertical position when in use or be swung into inoperative position adjacent the top of said oven and at the same time permit its sliding movement into adjusted position with respect to the ends of 100 the oven for fixing the dimensions of the baking compartment.

The wall of said partition member adjacent the baking compartment is provided with horizontal ribs 22 corresponding to 105 the ribs 22½ horizontally positioned upon the inner end walls 10 of the oven for supporting the grid 24. The outer wall of said member is provided with downwardly extending aprons 23 which reach to the open 110 bottom of the oven and straddle the deflector plate 14 for preventing the spread-

ing of the flame or heat therefrom to the unused adjacent compartment. As shown in the drawings the partition member 20 is adjusted in operative position for dividing off the baking compartment 24 from the unused and unheated space 25. When it is desired to employ the inner compartment of the oven for any purpose, said partition member is caused to slide upon the rod 19 until the hook or eye 21 falls into the recess 26, when it is swung upwardly into the position shown by dotted lines in Fig. 2 and retained in said position by the hook 27, positioned to engage the holes 28 on the 15 ends of the aprons 23.

In the modified form shown in Figs. 4 and 5, the partition member 120 is fixedly hinged to the top of the oven 18 by means of the hinge 30 rigidly secured thereto. 20 Wherein the dimensions of the oven prevent said partition from swinging into the horizontal position adjacent the top out of the oven, it is so arranged as to be telescopically adjusted by means of the extension member 121 which is slidably mounted in the main body of the partition member. When in extended vertical position, as shown in Fig. 4, it serves as a partition in the same manner as above described, and 25 when swung into horizontal position, as shown in dotted lines, the extension member is telescoped into the partition member 120. In this modified form the aprons 123 are provided for the purpose and in the same manner as above described with respect to the apron 23, and said members 120 and 121 are likewise provided with horizontal ribs 122. The front end of the partition is held against the top of the oven 30 by means of a suitable lock 127.

For preventing the flame and heat from the burner from passing over to the unused chamber, there is provided a partition 29 in addition to the aprons 23, said partition 45 being secured to the flame spreader and extending across the oven chamber.

The invention claimed is:

1. The combination with an oven having an open bottom, and means for heating said 50 oven, of a nonconducting partition wall disposed within said oven hingedly mounted upon a member thereof, which may be swung within said oven to form a partition, a horizontally disposed flame protecting 55 member mounted in said oven, and aprons mounted on said wall in position to extend beyond said member when said wall is in operative position.

2. The combination with an oven having

an open bottom, and means for heating said 60 oven, of a nonconducting partition wall disposed within said oven and hingedly mounted upon a member thereof, which may be swung within said oven to form a partition, and an extension member mounted 65 on said partition wall adapted to extend across said oven for forming part of the partition when in extended position, and permit said partition to be positioned against the member upon which it is hinged 70 when in contracted position.

3. The combination with an oven having an open bottom, and means for heating said 75 oven, of a nonconducting partition wall disposed within said oven and hingedly mounted upon a member thereof, which may be swung within said oven to form a partition, and an extension member slidably mounted upon the partition wall for permitting it to be extended in position to 80 form a partition for the oven chamber and to lie adjacent the member to which it is hinged when in contracted position.

4. The combination with an oven having an open bottom, and means for heating said 85 oven, of a nonconducting partition wall disposed within said oven, supporting rods secured to a member of said oven, supporting means hingedly connecting said partition wall with said rods, whereby said 90 partition may be swung into operative position to form a partition in said oven and into inoperative position against one of said oven members, and means for locking said partition in inoperative position adjacent the member upon which it is hinged. 95

5. The combination with an oven having an open bottom, means for heating said oven, a horizontal flame spreading plate mounted in said oven near the bottom 100 thereof, and a dividing wall secured under said plate and extending transversely of said oven.

6. The combination with an oven having an open bottom, means for heating said oven, a non-conducting partition wall disposed within said oven adapted to be adjusted therein to form a partition whereby said oven will be divided into a plurality of chambers, a horizontal flame spreader 110 member secured within said oven near the bottom thereof, and a dividing wall secured under said plate and extending transversely of said oven.

In witness whereof, I have hereunto af- 115 fixed my signature.

HERBERT C. TAYLOR.
